BOILER FURNACE

Max H. Kuhner, Worcester, Mass., assignor to
Riley Stoker Corporation, Worcester, Mass., a
corporation of Massachusetts

Application September 23, 1932, Serial No. 634,576

5 Claims. (Cl. 122—302)

This invention relates to boiler furnaces, and more particularly to the construction and arrangement of a pair of boilers mounted above a common furnace chamber.

5 Steam boilers are frequently mounted in a battery, that is, the boilers are side by side, and a central or "battery" wall separates the respective furnace chambers. Such boilers are usually equipped with stokers or with grates adapted for 10 hand-firing. When it is desired to modernize steam generating equipment of this type and to utilize pulverized coal as the fuel, it is ordinarily found that the furnace chambers are too narrow to give satisfactory results.

15 This difficulty can be met by removing the lower portion of the battery wall, thus providing a single large furnace chamber for the two boilers. However, the upper portion of the battery wall must be retained to prevent short circuiting of the 20 hot gases through the space between the boilers. As yet, no satisfactory construction has been proposed for supporting this wall.

25 It is accordingly the main object of the present invention to provide a simple, practical and inexpensive construction for supporting a wall between a pair of boilers, whereby both boilers may be heated by means of gases from a common furnace chamber therebeneath.

30 It is a further object of the invention to provide a simple and durable construction which will allow the lower portion of the battery wall in a battery setting to be removed, thus forming a single large furnace chamber in which pulverized coal may be burned in suspension.

35 With these and other objects in view, as will be apparent to those skilled in the art, the invention resides in the combination of parts set forth in the specification and covered by the claims appended hereto.

40 In accordance with the invention, the upper portion of the battery wall is supported on a beam which extends from front to rear between the boilers. This beam is preferably hollow, and may be cooled by the circulation of water therethrough. In the preferred construction, the hollow beam slopes at a slight angle with the horizontal, and is connected into the circulation of one or both of the boilers. The ends of the beam 45 may rest upon transverse beams which are supported by the boiler columns.

45 Referring to the drawing illustrating one embodiment of the invention, and in which like reference numerals indicate like parts,

50 Fig. 1 is a longitudinal section through a boiler

furnace, the section being taken substantially on the line 1—1 of Fig. 3;

5 Fig. 2 is a section on the line 2—2 of Fig. 1, a portion being broken away for clearness of illustration; and

Fig. 3 is a section on the line 3—3 of Fig. 1.

In the drawing I have illustrated two steam boilers of the well-known Badenhausen type mounted side by side above a furnace chamber 10. The furnace chamber is provided with a front 10 wall 11, a rear wall 12, and two side walls 14. A battery wall 15 is positioned between the boilers and extends longitudinally thereof.

Each boiler comprises a rear water drum 16 above the rear wall 12, a front water drum 18 15 above the front wall 11, and a steam and water drum 19 above the rear drum 16. These drums are all arranged transversely of the furnace chamber 10, and they are connected by three banks of water tubes to form a complete circulating system. As illustrated, tube bank 21 slopes 20 upwardly and forwardly between drums 16 and 18, tube bank 22 slopes upwardly and rearwardly between drums 18 and 19, and tube bank 23 extends substantially vertically between drums 19 25 and 16. A steam drum 25 is mounted above the front water drum 18, and a row of substantially horizontal tubes 26 leads from the steam and water drum 19 to the steam drum. These tubes 26 support refractory material 27 which forms a 30 roof for the boiler. A wall 29 is provided in the rear of the tube bank 23, and a gas outlet 30 is located between the upper portion of this wall and the steam and water drum 19. Baffles 31 35 direct the hot gases from the furnace chamber 10 successively over the tube banks 21, 22, and 23 to the outlet 30. This generates steam which is delivered to the steam and water drum 19 and then flows through the tubes 26 to the steam drum 25.

In a boiler furnace of this type, the battery 40 wall 15 ordinarily extends downwardly and divides the space beneath the boilers into two entirely separate furnace chambers, neither of which is of sufficient width for satisfactory operation with pulverized coal. In order that pulverized coal may be used as a fuel, I have removed the lower portion of the battery wall, thus forming a single combustion chamber of ample width. The upper portion 15 of the battery wall is retained to prevent the hot gases from flowing 45 through the space between the boilers instead of through the tube banks.

50 In the embodiment illustrated I have arranged to support the wall 15 by means of a hollow beam 33, rectangular in cross-section, which extends 55

from front to rear between the two boilers. The ends of this beam extend outside the furnace walls and rest upon transverse beams 34 which are supported by the boiler columns 35. Other suitable means may be provided for supporting the ends of the beam 33. This beam 33 preferably slopes upwardly at a slight angle toward the front, and it is shown connected into the circulation of both the boilers. For this purpose, tubes 37 connect both the drums 16 with the lower end of the beam, and tubes 38 connect both the drums 18 with the upper end of the beam. A drain pipe 39 is preferably provided at the lower end of the beam, and handhole caps 41 are provided at each end of the beam. Small angles 42 are welded or otherwise secured to the upper surface of the beam to form lugs which assist in anchoring the wall 15 thereon. It will be noted that the beam 33 extends above the drums 16 and below the drums 18.

In order to prevent gases from flowing from the furnace chamber rearwardly beneath the beam 33, a small brick pier 43 is constructed in front of the drums 16 and between the rear portions of the tube banks 21. This pier 43 extends upwardly to the lower surface of the beam 33.

When the beam 33 is installed, it will be possible in some cases to shore up the upper portion of the existing battery wall. In other cases, it will be easier to remove the entire battery wall, and after the beam is installed build a new wall on top of the beam. It is immaterial, so far as the present invention is concerned, which of these methods is followed.

The operation of the invention will now be apparent from the above disclosure. Pulverized coal or a similar fuel is burned in suspension in the furnace chamber 10, which is of sufficient width to avoid flame impingement on the side walls. The hot gaseous products of combustion are divided above the furnace chamber by the pier 43, beam 33 and wall 15, and these gases flow in contact with the boiler tubes, thus generating steam. The beam 33 forms a strong, simple and relatively inexpensive support for the wall 15. Water flows from the drums 16 through the tubes 37 into the lower end of the beam 33, and then upwardly and forwardly along the beam. The water, together with any steam generated in the beam, flows from the upper end of the beam through the tubes 38 into the drums 18. This continuous circulation of water through the beam prevents any possibility of overheating thereof. Furthermore, the beam protects the refractory wall 15 from the direct impingement of the hot gases.

It will be apparent that I have provided a simple and practical means whereby two boilers, originally set in a battery with separate furnace chambers, may be arranged to be fired from a single large furnace chamber. The invention, in its broader aspects, is susceptible of considerable change in its mode of application, and may be used with boilers of various types differing from those illustrated.

Having thus described my invention, what I

claim as new and desire to secure by Letters Patent is:

1. A boiler furnace comprising walls forming a furnace chamber, two boilers mounted side by side above the furnace chamber, each boiler having a transverse lower drum at the rear, a transverse upper drum at the front, and a bank of tubes connecting the drums, a hollow beam extending above the rear drums and beneath the front drums, said beam being located between the boilers and sloping upwardly toward the front, a water flow connection between one lower drum and the rear end of the beam, a water flow connection between one upper drum and the front end of the beam, and a battery wall above and supported by the beam. 5

2. A boiler furnace comprising walls forming a furnace chamber, two boilers mounted side by side above the furnace chamber, a battery wall extending longitudinally between the boilers, 20 a hollow beam extending above the furnace chamber and beneath the battery wall to support the same, the ends of the beam extending outside the furnace walls, means to support the ends of the beam, and means to circulate water 25 through the beam.

3. A boiler furnace comprising walls forming a furnace chamber, two boilers mounted side by side above the furnace chamber, each boiler having a transverse lower drum at the rear, a transverse upper drum at the front, and a bank of tubes connecting the drums, a hollow beam extending above the rear drums and beneath the front drums, said beam being located between the boilers and sloping upwardly toward the 35 front, a water flow connection between one lower drum and the rear end of the beam, a water flow connection between one upper drum and the front end of the beam, a battery wall above and supported by the beam, and means to prevent gases from flowing rearwardly from the furnace chamber between the beam and the lower drums. 40

4. A boiler furnace comprising walls forming a furnace chamber, two boilers mounted side by 45 side above the furnace chamber, a hollow beam located above the furnace chamber and between the boilers, the ends of the beam extending beyond the walls of the furnace chamber, supporting means for the ends of the beam, means to circulate water through the beam, and a battery wall above and supported by the beam. 50

5. A boiler furnace comprising walls forming a furnace chamber, two boilers mounted side by side above the furnace chamber and each having a bank of tubes which slopes upwardly toward the front of the furnace chamber, the furnace chamber extending throughout substantially the entire length of the banks of tubes, a hollow beam located above the furnace chamber and between the boilers, the beam sloping upwardly toward the front of the furnace chamber, means connecting the ends of the beam with the interior of one of the boilers, and a battery wall above and supported by the beam. 60 65
